UNITED STATES PATENT OFFICE.

GEORGE K. WEBSTER, OF ATTLEBOROUGH, MASSACHUSETTS.

SEPARABLE BUTTON.

SPECIFICATION forming part of Letters Patent No. 225,896, dated March 23, 1880.

Application filed November 6, 1879

To all whom it may concern:

Be it known that I, GEORGE K. WEBSTER, of Attleborough, in the county of Bristol and State of Massachusetts, have invented a new and useful Improvement in Separable Buttons; and I do hereby declare that the following is a full, clear, and exact description of the same.

My invention relates to separable buttons for collars or sleeves, and is also applicable to shirt-studs.

The object of the invention is to facilitate and cheapen the manufacture of separable buttons.

15 I have hereinafter fully and particularly described the form and arrangement of the parts which constitute my invention, and have specifically pointed out said invention in the claim.

In the drawings hereto attached, and forming part of this specification, Figure 1 is a perspective view of the button; Fig. 2, a transverse section longitudinally through the pushers, catches, and spring.

25 In the form shown by me the posts, mode of holding the posts together, and means for releasing the catches are, generally speaking, like those heretofore known.

In the drawings, *a* represents the outer disk or face, and *b* the inner disk or shoe, of the button.

30 To the inner disk, *b*, is soldered the hollow post *c*, slightly flattened, and slotted on the edges. Another post, *d*, similar in shape, and also hollow, and adapted to fit snugly into the first, is fixed to the outer disk or face, *a*. This outer face has a slot, forming the opening into the inner post.

35 The catches and pushers are, preferably, formed out of a single piece, which is shown at *e* in Fig. 2. This piece consists of the arms 11, which constitute the pushers, by which the catches may be unloosened, and of the catches 22, formed on the sides of the bow, which projects into the inner hollow post.

40 The ends of the pushers project through the side of the shell of the outer disk, and such ends may be covered with a facing of gold, or may be ornamented in any way as taste may dictate.

The arms are inclosed, except at the projecting ends, within the hollow body of the outer disk.

Within a recess, 3, formed in the loop 6 of the part *e*, is placed a small steel spring, 5, of U shape, the function of which is to keep the bow of the piece well spread, so as to hold the catches 22 in connection with the outer post. These catches project through the slots both of the inner and outer posts, and the horizontal faces of the catches bear, when the parts 60 are in place, against the ends of the slots in the outer post, as shown at 44, whereby the two parts of the button are securely held together.

The posts may be made separately of sections of flattened tubes slotted at proper lengths on the edges and then soldered to their respective disks. Then the bow of the part *e*, with the spring 5 in place, is inserted through the slot in the outer disk into the inner post.

A hole, *x*, is made through the inner post at the center, so that a pin may be inserted through the space between the arms of the spring to hold the part *e* in place. This pin, 75 however, is not essential, as the part *e* is held by the outer shell of the face of the button, which is put on after the piece or part *e* is inserted, and either soldered or held by turning over the edge of its flange.

80 The outer or ornamented surface of the face may be made of gold, or may have a stone, or any of the ordinary ornaments. The button itself may be of gold or other metal.

What I claim as my invention, and desire to secure by Letters Patent, is—

85 In combination with the part *e*, having arms 11, and a looped central part provided with catches, the spring 5, adapted to the other parts, as set forth.

90 In testimony whereof I have signed my name to this specification in the presence of two subscribing witnesses.

GEORGE K. WEBSTER.
